UNITED STATES PATENT OFFICE.

NAPOLEON B. DOUGLASS, OF BERKELEY, CALIFORNIA.

FOLDING BED.

1,344,995.

Specification of Letters Patent. Patented June 29, 1920.

Application filed September 3, 1919. Serial No. 321,442.

To all whom it may concern:

Be it known that I, NAPOLEON B. DOUGLASS, a citizen of the United States, residing at Berkeley, in the county of Alameda and 5 State of California, have invented new and useful Improvements in Folding Beds, of which the following is a specification.

This invention relates to folding beds and more particularly to a latch mechanism for 10 a hinged member of the bed.

The object of the invention is to conceal the latch mechanism in such manner that no part thereof will be visible. This is accomplished by employing a tubular construction 15 for the hinged portion and locating the latch within the tubular member. The latch ordinarily is employed in connection with hinged legs or hinged foot pieces of a folding bed and it will be understood that such 20 parts of the bed are ordinarily constructed of tubular members.

In the accompanying drawing—

Figure 1 shows a plan view of a folding bed frame.

25 Fig. 2 shows an elevation of a portion of the outer end of the bed wherein the supporting leg is hinged and the latch therefor is indicated by dotted lines.

Fig. 3 shows a sectional view of one form 30 of latch mechanism.

Fig. 4 shows a sectional view of a modified form of latch mechanism.

Fig. 5 shows a sectional view of a still 35 different form of latch mechanism wherein the latch is controlled by gravity.

Fig. 6 shows a similar view illustrating the parts in a different position.

Fig. 7 shows an elevation of a portion of the outer end of a folding bed illustrating 40 my latch mechanism employed in connection with a folding foot piece, as well as in connection with folding legs.

A bed frame is indicated generally by numeral 10 and is pivoted at its forward end 45 as shown at 10^a for folding movement. Included in the bed frame is a foot piece 11 having supporting legs 12. This foot piece and supporting legs are of tubular construction and the latter are hinged as shown at 13 50 to fold against the bed frame when the bed is in folded position.

In the form shown in Figs. 2 and 3, I provide a latch mechanism for the hinged members which comprises a leaf spring 14 mounted entirely within the tubular leg and 55 having a hook 15 at its free end, which hook

cooperates with a beveled lug 16 secured to the stationary or fixed portion of the bed frame. The operation of this latch mechanism will readily be understood. When it is 60 desired to fold the bed, pressure is applied to the leg in the direction to fold the same whereupon the spring 14 yields sufficiently to disengage itself from the lug 16. In extending the bed, the folding leg is moved to 65 extended position, whereupon the hook shaped end 15 of the spring rides over the beveled face of the lug 16 and seats itself back of the lug whereby to retain the leg in 70 extended position.

A modified form of the latch is shown in Fig. 4, wherein the lug 16 has been omitted. In this form the spring 14 presses outwardly 75 against the wall of the tubular member 11 and retains the hinged leg in extended position by reason of frictional contact. The free end of the leaf spring is so shaped and positioned with respect to the hinge that flexing of the leaf spring is necessary to move the leg to folded position and the hook 80 is extended so that its beveled portion will engage with the end 17 of the foot piece when the leg is being moved to extended position and ride thereover, seating itself on the inside of the tubular member 11. 85

In the form shown in Figs. 5 and 6, I make use of a gravity hook. This comprises a hook-shaped member 18 pivoted to one of the tubular members at 19 and cooperating 90 with a lug 20 carried by the other tubular member. The hook 18 is so shaped and balanced that when the bed is in folded position, which ordinarily represents the vertical position of the bed frame, the outer end of the hook 18 will overbalance the inner 95 end allowing the hook to drop down as shown in Fig. 6, thereby releasing the lug 20, whereupon the leg 12 may be moved downwardly to folded position. As the bed frame is swung from a vertical to a horizontal position as in unfolding, the hook 18 gradually assumes an upright position, such as shown in Fig. 5, and in this position pivot 19 is so placed with reference to the hook that the hook-shaped end of the member 100 will swing in the opposite direction to re-engage the lug 20, thereby latching the leg in extended position. This is so because of the uneven distribution of the weight of the hook-shaped member considered in a longitudinal direction. 105

In Fig. 7 I show a foot piece 11 wherein

the up-standing or bail-shaped portion 11^a is hinged, one or the other of the forms of concealed hinges already described being used to latch the hinged foot piece in upright position. By so hinging this upstanding portion of the foot piece, it may be dropped inwardly against the bed clothing when the bed is folded and thereby the thickness of the folded bed is considerably reduced, and I am enabled to materially reduce the depth of the closet or recess in which the bed is stored. This is an item of considerable importance in connection with wall beds.

Having thus described my invention, what I claim and desire to secure by Letters Patent is:

1. In a folding bed, a tubular frame member having a tubular part hingedly connected thereto and a latch for said hinge connection comprising a gravity operated pawl pivotally mounted within one of the tubular parts and extending into the other, said pawl being operative when the bed frame is

in horizontal position to retain the parts in extended position, and when the bed frame is vertical to release the parts and allow them to be folded.

2. In a folding bed, a tubular frame member having a tubular part hingedly connected thereto and a latch for said hinge connection comprising a gravity operated pawl pivotally mounted within the tubular frame member and extending into the hinged tubular part, and a lug in the latter with which the pawl co-operates, said pawl being operative when the bed frame is in horizontal position to engage the lug and retain the parts in extended position and when the bed frame is in vertical position to disengage the lug and allow the parts to be folded.

In testimony whereof I have hereunto set my hand in the presence of two subscribing witnesses.

NAPOLEON B. DOUGLASS.
